UNITED STATES PATENT OFFICE.

JAMES M. CONNER, OF GREENVILLE, NEW JERSEY.

DESIGN FOR PRINTING-TYPES.

Specification forming part of Design No. 7,750, dated September 8, 1874; application filed August 25, 1874.
[Term of Patent 7 years.]

CASE A.

To all whom it may concern:

Be it known that I, JAMES M. CONNER, of Greenville, Hudson county, New Jersey, have invented and produced a new and original Design for Printing - Type, of which the following is a specification:

The nature of my design is clearly shown in the accompanying typographic impression, to which reference is made; and consists in a

black letter, shaded and ornamented as fully shown.

What I claim as new is—

The design for a font of printing - types, as herein shown and described.

JAMES M. CONNER.

In presence of—

W.M. C. CONNER, Jr.,
JOSEPH J. DUNN.
